UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

CLUSTER LAMP-SOCKET.

No. 852,439.

Specification of Letters Patent.

Patented May 7, 1907.

Application filed January 31, 1903. Serial No. 141,262.

To all whom it may concern:

Be it known that I, REUBEN B. BENJAMIN, a citizen of the United States, residing at Chicago, in the county of Cook and State of Illinois, have invented a certain new and useful Improvement in Cluster Lamp-Sockets, of which the following is a full, clear, concise, and exact description, reference being had to the accompanying drawing, forming a part of this specification.

My invention relates to improvements in cluster sockets for electric lamps.

It has for its object to provide a device of this character which is cheap of manufacture, efficient, safe and durable in use.

In the accompanying drawings the several views are as follows:

Figure 1 is a side elevation of my improved device, in the form which will connect the lamps in circuit in multiple, Fig. 2 is a similar view with parts broken away, Figs. 3 and 4 are views of opposite ends of the device, Fig. 5 is a partial longitudinal vertical section, Fig. 6 is a cross section on the line 6—6 of Fig. 2, Fig. 7 is a sectional view through the base on the line 7—7 of Fig. 3, Fig. 8 is a sectional view through a base provided with terminals for connecting the lamps in series instead of in parallel as in the preceding structure, Fig. 9 is a similar view of a base formed in a single piece and provided with terminals which will connect the lamps in circuit in multiple, Fig. 10 is an elevation of a modified form of my invention, Fig. 11 is an end view thereof, Fig. 12 is an end view with the casing on that end removed, Fig. 13 is a longitudinal vertical sectional view on the line 13—13 of Fig. 11, one of the bushings being in elevation, and, Fig. 14 is a horizontal sectional view taken through the base in this modification on the line 14—14 of Fig. 12.

Throughout the drawings like reference characters designate similar and corresponding parts.

Referring to Figs. 1 to 7 inclusive, in carrying out my invention in its preferred form as shown therein, I provide a base which is preferably constructed of two circular disks 2, 2 of porcelain or other insulating material. The base is recessed or cut out on opposite sides as at 3, and has a groove 4 in its periph-

ery which connects said recesses. The central portion of a metallic strip 5 rests within one of said recesses and has its ends 6 bent inwardly. The extremities of said ends project slightly beyond the center of said base and are arranged away from the sides thereof so that they may spring. One has a tongue 7, preferably, struck up therefrom which bears against the side of the base. A screw 8 which has its head bearing upon the other side of the base extends through a hole 9 in said base and is threaded into said tongue to secure the strip 5 in position. The other end of said strip has a hole 10 through which an implement for turning the screw may be inserted and the portion of said strip within the recess in said base is provided with a binding screw 11. A threaded lamp receiving shell 12 is arranged on each side of the base and secured thereto by screws 13 which pass through the base and electrically connect said shells. The heads of said screws bear upon inturned portions 14 of the shell on one side of the base. The other shell has similar inturned portions upon which bear a preferably curved plate 15 into which are threaded the ends of the screws. This curved plate is provided with a lug 16 which is bent into the recess 3 opposite the one in which rests the strip 5 and is provided with a binding screw 17. The shells and the parts associated therewith, and the strips 5 and likewise its associate parts are insulated from each other by the base. A preferably tubular casing 18 surrounds each shell and an insulating sheath 19 is interposed between said casings and the shells. The sheath for the two shells is preferably formed in one piece. The ends thereof project beyond the ends of said shells and casings and its central portion incloses the base. In order that access may be had to the binding screws and the groove or channel in the periphery of the base this sheath is suitably perforated. The two casings are held in their proper positions by a ring 20 provided with inwardly turned edges 21 which overlap outwardly flared inner edges 22 of said casings. This ring is made in two parts which are preferably joined together by inwardly turned lugs 23 formed on the ends of one part which project into eyes 24 perforated in the ends of the

other part. By this construction the two parts may be readily separated and assembled. The inclosing casing of the socket, it will be noted, is of such diameter that it lies closely to the lamp receiving shells and is of such length that when the lamps are inserted in position, it stops short of the lamp bulbs and does not cover the same, nor interfere with the insertion of the lamps in position. The upper part of said ring is provided with a screw 25 which is turned to bear upon the base in a recess therein and thereby spread the ring which will operate to grip the parts thereof tightly together and secure the casings in their relative positions. The lower part of said ring is preferably secured to a tubular standard 26 for supporting the device and has a hole 27 therein arranged opposite the tube. This construction permits the supply wires to be led up through the support into the casing, around the base in the peripheral groove therein, and connected with their respective terminals by the binding screws. One wire is connected to the binding screw electrically connected with the receiving shells and the other wire is joined to the strip 5 by the other binding screw. The ends of said strip constitute the center contacts and engage the inner contacts of lamps inserted into the receiving shells. The spring action of said center contacts insure a good contact. When the lamps are in position the circuit for each lamp will be from one wire to the receiving shells, thence through the lamps, and back to the other wire by the way of the center contacts. In this form of my device the lamps are connected in circuit in parallel. Removal of the upper portion of the ring permits access to the binding screws, thus enabling the supply wires to be easily connected with their respective terminals.

In Fig. 8 is shown a base on which the contact terminals for the lamps are arranged to connect said lamps in circuit in series instead of in multiple as in the devices heretofore disclosed. The two lamp receiving shells are mounted on opposite sides of the base and are electrically connected but have no connection with the supply wires except when the lamps are in position. Also on each side of the base is a center spring contact 29 which is secured in place by a screw 30 which is threaded into a tongue 31 preferably struck up from said contacts. Each screw passes through a central aperture in one of the parts of the base and has its head countersunk in the meeting face of the part of the base through which it passes. The heads of the screws are separated from each other by an insulating disk 32. The outer end of each contact extends around into one of the recesses in the base and is provided with a binding screw 33 for securing thereto

one of the supply wires. The lamps supported by this form of my invention will be connected in circuit in series, and the circuit for the current will be from one of the center contacts through the lamp in contact therewith to the receiving shells and then through the other lamp to the center contact which is in contact therewith and connected to the other supply wire. In the structure just described the base is made in two parts, so that the screws for fastening the center contacts in position may be placed as described and the two parts are held together by screws which pass therethrough and mechanically support and electrically connect the receiving shells.

Although the base shown and described in the first disclosed embodiment of my invention is made in two parts, yet it may be constructed in a single piece, as shown in Fig. 9. In that instance, the object of making it in two parts is to facilitate the manufacture thereof. The single piece base is recessed as my preferred form of base, and has its periphery provided with a bead 33^a which is arranged near one side of the base. A disk 34 of insulating material is arranged upon the opposite side of the base, and its edges extend beyond the edge of the base whereby a channel having insulating walls is provided for the supply wires. Said disk has a central perforation into which extends a protuberance on the base and is held between one of the receiving shells and the base.

The structure shown in Figs. 10 to 14 is a modified form of the construction before described. In this device there is a base 35 consisting of a disk of insulating material. The bottom of the base is preferably recessed as at 36. The base has a hole 37 provided therein through which passes a strip 38, the ends 39 of which are bent to receive the base between them. Said ends are arranged away from the faces of the base and constitute the center contacts for the lamps. The strip is retained in position by a screw 40 which passes through the base. The head of said screw bears upon one side of the base and is threaded into a tongue 41 which is preferably, struck up from the strip and bears on the opposite side of said base. The lamp receiving shells are supported on the base by screws 42 which also serve to electrically connect said shells. The heads of these screws bear directly upon the inturned portion of one shell and their opposite ends are threaded into a curved plate 43 which bears upon the inturned portions of the shell on the other side of the base. This plate has a lug 44 which extends into a recess 45 in one of the faces of the base. Said lug is provided with a binding screw 46 for connecting therewith one of the supply wires and the other supply wire is to be connected

- to the center contacts by a binding screw 47 upon the portion thereof which is arranged within the hole in said base. A groove or channel 48 is provided in one of the faces of the base which leads from the cut out portion at the bottom of said disk to the hole and recess in which are arranged the binding screws. In this groove are laid the supply wires which are led to and connected with their respective terminals. The base is surrounded by a ring 49 which, preferably has an annular shoulder on its opposite edges. A preferably tubular support 50 is secured to said ring; and a hole 51 in said ring communicates with the cut-out portion 36 of the base and the hole in the tube which enables the supply wires leading to the respective terminals to be entirely inclosed. A close lying casing 52 for the receiving shells rests upon the shoulder on each side of the ring and the ends of said casing abut against annular flanges 54 of bushings 53, which separate the casing from the receiving shells. These bushings are threaded upon the receiving shells and have the ends thereof substantially flush with the mouths of the receiving shells. By this arrangement when the lamps are in position, the inclosing casing stops short of the lamp bulbs and does not interfere with the insertion of the lamps. This form of my device connects the lamps supported thereby in circuit in multiple. The circuit for the current will be from the center contacts through each lamp to the outer contacts or receiving shells.
- This improved lamp cluster is particularly advantageous for use in show windows. There are, however, many other places wherein it may be used to equal advantage.
- While there is shown a standard for supporting the device it may be desirable that it be held in position by other means. In lieu of the standard there might be provided a plug for insertion into the ordinary lamp receiving socket, said plug having inner and outer contacts which would connect the respective terminals of the lamp cluster and the socket for the plug. Furthermore, by slight modification in any form of my device the lamps may be connected in circuit either in series or parallel.
- Herein is shown and described only the most obvious manner of embodying my invention in a practical device, and, therefore, I reserve the right to make such changes in the details of construction, arrangement and combination of parts as fairly fall within the scope of my invention.
- Having described my invention what I claim as new and desire to secure by Letters Patent is:
1. In an electric lamp cluster, the combination of lamp receiving shells arranged upon opposite sides of a common base, and a ring for supporting said base made in two sections 65 adapted to be separated one from the other, substantially as described.
  2. In an electric lamp cluster, the combination of lamp receiving shells arranged upon opposite sides of a common base, a ring for supporting said base made in two sections 70 adapted to be separated one from the other, and means for clamping said ring to said base, substantially as described.
  3. In an electric lamp cluster, the combination with a suitable base, of lamp receiving shells arranged upon opposite sides thereof, a casing surrounding each of said shells and having an unobstructed opening in the end thereof to permit the insertion of a lamp in 80 the shell, and a ring for retaining said casings in their normal position, substantially as described.
  4. In an electric lamp cluster, the combination with lamp receiving shells arranged 85 upon opposite sides of a common base, of a casing surrounding each of said shells having an unobstructed opening in the end thereof to permit the insertion of a lamp in the shell, said casings being joined together by a ring 90 to retain them in their normal position, substantially as described.
  5. In an electric lamp cluster, the combination with lamp receiving shells arranged upon opposite sides of a common base, of 95 casings for said shells having flared edges, and a ring arranged between said casings also having flared edges which overlap the flared edges of said casings whereby they are retained in their normal position, substantially as described.
  6. In an electric lamp cluster, the combination with a suitable base, of lamp receiving shells arranged upon opposite sides thereof, casings for said shells and a ring for securing 105 said shells in their relative positions, said ring being constructed in two parts which may be readily separated, substantially as described.
  7. In an electric lamp cluster, the combination with a base having lamp receiving shells arranged on opposite sides thereof, of casings for said shells and a ring for securing said casings in their relative positions, said ring being composed of two parts which may 110 be readily separated or joined together, and means for clamping said ring to said base, substantially as described.
  8. In an electric lamp cluster, the combination with a suitable base, of lamp receiving shells arranged upon opposite sides thereof, an inclosing casing for each shell, a ring made in two parts, adapted to retain said casings in their normal positions, means for securing 120 said parts together, and an insulating sheath 125 interposed between said casings and said receiving shells, substantially as described.
  9. In a two light electric lamp cluster, the

- combination with an elongated inclosing portion of minimum transverse dimension having recesses formed in the opposite ends thereof, adapted to receive electric lamp bases and arranged to support the same substantially in axial alinement, of a suitable support for said inclosing portion, and a single pair of binding posts common to the two lamp receptacles substantially as described.
10. In a two light electric lamp cluster, the combination with an elongated inclosing sheath of minimum transverse dimension, of lamp receiving shells disposed within the opposite ends of said sheath and arranged to support the lamps substantially in axial alinement, a pair of binding posts common to the two lamp receivers and a suitable support for said sheath, substantially as described.
11. In a two light electric lamp cluster, the combination with an elongated inclosing portion of minimum transverse dimension having recesses provided in the opposite ends thereof adapted to receive electric lamp bases and support the lamps substantially in axial alinement, of a tubular support for said inclosing portion, said support constituting a conduit for supply wires and a pair of binding posts common to the two lamp receptacles, substantially as described.
12. In a two light electric lamp socket, the combination with an elongated inclosing portion, of lamp receivers provided in the opposite ends thereof, said inclosing portion being provided with a removable part to permit access to the interior of the socket, substantially as described.
13. In a two light electric lamp socket, the combination with an elongated inclosing portion, of lamp receivers in the opposite ends thereof, a binding post common to the outer contacts of each lamp receiver, a second binding post common to the center contacts of the two lamp receivers, said inclosing portion being provided with a removable part to permit access to the binding posts, substantially as described.
14. In a two light electric lamp cluster, the combination with an insulating base or support, of lamp receivers and associated contacts mounted upon said base to maintain the lamps substantially in axial alinement and a metal casing surrounding said base and lamp receivers and having a portion thereof removable to permit access to the interior of the socket, substantially as described.
15. In a two light electric lamp cluster, the combination with an insulating base or support, of lamp receivers and associated contacts mounted upon opposite sides thereof, binding posts suitably supported upon said base, a metallic shell inclosing said base and lamp receivers, and suitable insulating means between said shell and said lamp receivers, a portion of said metallic shell being remov-
- able to permit access to said binding posts, substantially as described.
16. In a two-light electric lamp cluster, the combination with a centrally disposed insulating base, of lamp receiving shells mounted upon opposite sides of said base and arranged to support the lamps substantially in axial alinement, and a casing surrounding said shells and having unobstructed openings in the ends thereof to permit the insertion of lamps in said shells, substantially as described.
17. In a two light electric lamp cluster, the combination with an insulating base, of lamp receiving shells mounted upon said base and supporting the lamps substantially in axial alinement, a casing for each of said shells having upturned inner edges and a casing for said base having downwardly extending edges, the upturned edges of said first mentioned casings co-acting with the downwardly extending edges of said second mentioned casing to retain said first mentioned casings in position and means for detaching said second mentioned casing to afford access to the interior of said socket, substantially as described.
18. In a two light electric lamp cluster, the combination with an insulating base, of lamp receiving shells mounted upon said base and supporting the lamps substantially in axial alinement, binding posts for supply wires mounted upon said base, a casing for each of said shells having upturned inner edges, a casing for said base composed of two members having downwardly extending edges, means for attaching one of said members to a suitable conduit or support and means for detachably securing another of said members in position, the upturned edges of said first mentioned casings and the downwardly extending edges of said second mentioned casings co-acting with said last mentioned means to retain said casings in position and to afford access to said binding posts through the sides of said socket, substantially as described.
19. In a two light electric lamp cluster, the combination with an insulating base, of lamp receiving shells mounted upon said base and supporting the lamps substantially in axial alinement, a suitable casing for said shells and suitable insulating means between said casing and shells, substantially as described.
20. In a two light electric lamp cluster, the combination with an insulating base, of lamp receiving shells mounted upon said base and supporting the lamps substantially in axial alinement, a suitable casing for said shells and an insulating sheath between said casing and said shells, substantially as described.
21. In a two light electric lamp cluster, the combination with an elongated supporting portion having lamp receiving recesses ar-

5 ranged in opposite ends thereof and supporting the lamps substantially in axial alinement, of a metal casing for said supporting portion composed of three members and an insulating sheath composed of three members disposed between said supporting portion and said casing, substantially as described.

10 22. In a two light electric lamp cluster, the combination with an insulating base, of lamp receiving shells mounted upon said base and supporting the lamps substantially in axial alinement, a suitable casing for said shells and insulating rings disposed between said shells and the outer edges of said casing, substantially as described.

15 23. In a two-light electric lamp cluster, the combination with an insulating base composed of two members, of a lamp receiving shell mounted upon each of said members arranged to support the lamps substantially in axial alinement, and a casing surrounding said shells having unobstructed openings in the ends thereof to permit the insertion of lamps in said shells.

20 24. In a two light electric lamp cluster, the combination with an insulating base, of lamp receiving shells mounted thereon arranged to support the lamps substantially in axial alinement, a binding post common to said shells arranged in a recess in said base, a binding post common to the center contacts of the lamps also arranged in a recess in said base, said base having a groove formed therein communicating with said binding posts and adapted to receive supply wires and a central tubular support for said socket communicating with said groove and adapted to receive supply wires, substantially as described.

25 25. In a two light electric lamp cluster, the combination with an insulating base, of lamp receiving shells mounted upon said base arranged to support the lamps substantially in axial alinement, and means securing said shells in position on said base said means electrically connecting said shells one with the other, substantially as described.

30 26. In a two light electric lamp cluster, the combination with an insulating base, of lamp receiving shells mounted upon said base arranged to support the lamps substantially in axial alinement, a U-shaped piece having a turned-up extended portion disposed in the bottom of one of said shells, a binding post carried by said extended portion, and means extending through said base mechanically supporting said U-shaped piece and said shells in position and electrically connecting said shells one with the other, substantially as described.

35 27. In a two light electric lamp cluster, the combination with an insulating base, of lamp receiving shells mounted thereon arranged to support the lamps substantially in axial

40 alinement, a strip arranged in a recess in said base having the ends thereof bent to extend opposite the faces of said base to form center spring contacts for the lamps and a binding post mounted upon said strip, substantially as described.

45 28. In a two light electric lamp cluster, the combination with an insulating base, of lamp receiving shells mounted thereon arranged to support the lamps substantially in axial alinement, a strip arranged in a recess in said base and having the ends thereof bent to extend opposite the faces of said base to form center spring contacts for the lamps, a tongue formed in one end of said strip, a bolt or rivet extending through said base and co-acting with said tongue to retain said strip in position, one end of said strip having an aperture formed therein to permit access to said bolt, substantially as described.

50 29. In a two-light electric lamp socket, the combination with a pair of suitably supported lamp receivers arranged end to end and adapted to support the lamps in substantially axial alinement, of lamp contacts associated with said receivers, a suitable support for the socket, and a casing surrounding said lamp receivers having unobstructed openings in the ends thereof to permit the insertion of lamps in said receivers.

55 30. In a two-light electric lamp socket, the combination with a pair of suitably supported lamp receivers arranged end to end and adapted to support the lamps substantially in axial alinement, of lamp contacts for said receivers, a centrally disposed support for the socket, electrical conductors extending through said support, and a casing or cover surrounding said lamp receivers having unobstructed openings in the ends thereof to permit the ready insertion of lamps in said receivers.

60 31. In a two-light electric lamp socket, the combination with a pair of suitably supported lamp receivers arranged end to end and adapted to support the lamps in substantially axial alinement, of lamp contacts associated with said receivers, and a casing or cover surrounding said lamp receivers having unobstructed openings in the ends thereof to permit the ready insertion of the lamps in said receivers.

65 32. In a cluster or plural lamp socket, the combination with a support, of a metallic casing removably connected thereto, an insulating base supported by and within said casing, and a plurality of lamp receivers and their contacts mounted upon said base and within said casing.

70 33. In a cluster or plural lamp socket, the combination with a support, of a metallic casing removably connected thereto, an insulating base supported by and within said casing, a plurality of lamp receivers and their

contacts mounted upon said base and within said casing, and means for insulating said receivers from said casing.

34. In a cluster or plural lamp socket, the combination with a support, of a metallic casing removably connected thereto, an insulating base supported by and within said casing, a plurality of lamp receivers and their contacts mounted upon said base and within

said casing, and a pair of binding posts mounted upon said base.

In witness whereof, I have hereunto subscribed my name in the presence of two witnesses.

REUBEN B. BENJAMIN.
